UNITED STATES PATENT OFFICE

2,613,885

YARN OR THREAD HOLDER

Mary C. Tuttle, Menlo Park, Calif., assignor of twenty-five per cent to Leslie C. Gillen and twenty-five per cent to Theodore J. Portello, both of San Francisco, Calif.

Application July 11, 1950, Serial No. 173,125

8 Claims. (Cl. 242—139)

1

This invention comprises novel and useful improvements in a yarn or thread holder and more specifically pertains to a supporting device for a plurality of yarn or thread holding spindles for selectively positioning the same for most effective use.

The primary object of this invention is to provide a device for supporting a plurality of yarn or thread-holding spindles in selected positions to afford the maximum ease of access to a selected spindle and the thread carried thereby to facilitate knitting and similar occupations.

Yet another object of the invention is to provide an improved yarn or thread holder in conformity with the foregoing object in which a plurality of spindles of thread are removably and rotatably supported by a supporting assembly which in turn is oscillatably mounted upon a base for selectively positioning the various spindles of thread.

An additional object of the invention is to provide an apparatus in conformity with the foregoing objects in which a plurality of spindles of thread are mounted upon a support frame upon opposite sides of an axis of oscillation of the frame whereby the spindles of thread may be selectively elevated into easy accessible position; together with a guiding means for maintaining the thread spindles and their supporting members in an erect position during all phases of their pivotal movement.

These, together with various ancillary features and objects of the invention which will later become apparent as the following description proceeds, are attained by the present invention, a preferred embodiment of which has been illustrated, by way of example only, in the accompanying drawings, wherein:

Figure 1 is a perspective view showing one suitable form of apparatus incorporating therein the principles of this invention, a quantity of thread being illustrated wound upon one of the spindles ready for use;

Figure 2 is a vertical transverse sectional view taken substantially upon the plane indicated by the section line 2—2 of Figure 1, an alternative position of the parts being indicated in dotted lines therein; and

Figure 3 is a vertical longitudinal sectional detail view taken substantially upon the plane indicated by the section line 3—3 of Figure 1 and illustrating the manner in which the supporting frame is guidingly connected with the supporting base of the device.

Referring now more specifically to the accom-

2

panying drawings, wherein like numerals designate similar parts throughout the various views, it will be seen that the device as illustrated consists of a base in the form of a tray or the like within which is mounted a supporting assembly for movably carrying a plurality of thread spindles. The base, which may be of any desired shape, size and material, preferably includes a bottom 10, side walls 12, and a pair of end walls 14. Suitably journaled in any desired character of bearings, not shown, in the end walls 14 is an axle 16, which may be conveniently of non-circular cross-section, as clearly shown in Figure 2. One end of this axle preferably extends beyond one of the end walls and has secured thereto a nob or the like 18 by means of which the axle may be rotated in order to shift the supporting member as set forth hereinafter.

Fixedly secured in any desired manner to the axle 16, and preferably adjacent the opposite ends of the same, are a pair of supporting frame members 20, each of which includes a pair of arms 22 and 24 which are preferably disposed at an obtuse angle with respect to each other.

Pivoted upon the extremities of the arms 22 and 24 of each of the frame members 20, and adjacent the outer ends of these arms, are a pair of parallel support bars 26 which are disposed in parallel relation to the axle 16 and to each other, the upper surface of these support bars having longitudinally spaced sockets 28 adapted to receive the lower ends 30 of a plurality of spindles 32 having shoulders 34 for seating upon the upper surfaces of the bars 26 and having notches 36 in their upper ends. It is intended that a quantity of thread, yarn or other material shall be wound upon the spindles 32 with one end of the thread, as at 38, received in the notches 36, and with the thread forming a cylindrical roll, as at 40, with a loose end 42 by means of which the thread may be withdrawn from the spindle for use. It will thus be seen that the spindle of thread is removably and rotatably supported upon one of the support bars 26.

As will now be apparent from an inspection of the full and dotted line showings of Figure 2, the support frame assembly may be oscillated about the axle 16 to selectively elevate one of the support bars and the spindles carried thereby relative to those carried by the other support bar, whereby the spindles of a selected support bar may be rendered more accessible for use of the thread, or withdrawal or replacement of the

spindle.

Guiding means are provided for maintaining the support bars in an erect and non-oscillatable position during the oscillation of the frame about the axis of the axle 16. This guide means, shown more particularly in Figures 1 and 3, consists of laterally extending pintles or stub axles 44 carried by the outer extremities of the arms 22 and 24, these pintles being pivotally received in bores or apertures 46 formed in up-standing lugs 48 upon the upper surfaces of the support bars. Thus, the support bars are pivotally supported upon the pintles 44 at their upper ends and depend therefrom.

Each of the end plates 14 is provided with guideways, which, as illustrated, consist of arcuate guide channels or tracks 50 formed in the adjacent surfaces of the end plates 14 and struck upon arcs having appropriate centers. Extending from the ends of the support bars 26 and off-center with respect to the axes of the pintles 44 and the passages 46 are guide members 52 which are slidably received in the guideways 50. The proportions and contours are such that the members 52 riding within the guideways 50 will positively pivot the support bars about the pintles 44 to maintain the support bars in erect position at all phases of their oscillatory travel.

Conveniently, the outside edges of the arms 22 and 24 may be cut away or notched, as at 54, to provide clearance for the members 52 at the extreme ends of the travel of the same as shown in Figure 3.

It is evident that although the guide means illustrated has guide grooves for receiving guide members 52 carried by the support bars, a reverse arrangement could be provided and in fact numerous other equivalents could be employed to give the desired guided movement to the support bars. Further, although a pair of support frames 20 have been illustrated and described, it will be readily understood that either one or a plurality of such frames could be employed as desired without departing from the principles of this invention.

It will now be seen that by properly rotating the knob 18, the axle 16 will be shifted to cause the oscillatory movement of the support frame from the full line position shown in Figure 2 to the dotted line position shown therein, and that during this travel the spindles will be maintained in upright position at all times, the result of this travel being to selectively elevate the spindles of one support bar with respect to those of the other.

From the foregoing, the construction and operation of the device together with its many advantages will be readily understood, and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having thus disclosed and described the invention, what is claimed as new is as follows:

1. A thread holder comprising a base, a support mounted on said base for oscillatory motion about a horizontal axis, guide means operatively connecting said support to said base for oscillatory motion, thread holders carried by said

support upon opposite sides of its axis of oscillation.

5 2. A thread holder comprising a base, a support mounted on said base for oscillatory motion about a horizontal axis, guide means operatively connecting said support to said base for oscillatory motion, thread holders carried by said support upon opposite sides of its axis of oscillation, said support including an axle journaled in bearings on said base, frame members each having angulated arms fixedly secured to said axle, support bars parallel to said axle and mounted on said arms.

15 3. A thread holder comprising a base, a support mounted on said base for oscillatory motion about a horizontal axis, guide means operatively connecting said support to said base for oscillatory motion, thread holders carried by said support upon opposite sides of its axis of oscillation, said support including an axle journaled in bearings on said base, frame members each having angulated arms fixedly secured to said axle, support bars parallel to said axle and mounted on said arms, said guide means comprising arcuate guideways at each end of each support bar, members on said bars slidably received in said guideways.

20 4. A thread holder comprising a base, a support mounted on said base for oscillatory motion about a horizontal axis, guide means operatively connecting said support to said base for oscillatory motion, thread holders carried by said support upon opposite sides of its axis of oscillation, said support including an axle journaled in bearings on said base, frame members each having angulated arms fixedly secured to said axle, support bars parallel to said axle and mounted on said arms, said guide means comprising arcuate guideways at each end of each support bar, members on said bars slidably received in said guideways.

25 5. A thread holder comprising a base, a support mounted on said base for oscillatory motion about a horizontal axis, guide means operatively connecting said support to said base for oscillatory motion, thread holders carried by said support upon opposite sides of its axis of oscillation, said support including an axle journaled in bearings on said base, frame members each having angulated arms fixedly secured to said axle, support bars parallel to said axle and mounted on said arms, said guide means comprising arcuate guideways at each end of each support bar, members on said bars slidably received in said guideways, said thread holders comprising spindles rotatably and removably mounted on said support.

30 40 6. A thread holder comprising a base, a support mounted on said base for oscillatory motion about a horizontal axis, guide means operatively connecting said support to said base for oscillatory motion, thread holders carried by said support upon opposite sides of its axis of oscillation, said support including an axle journaled in bearings on said base, frame members each having angulated arms fixedly secured to said axle, support bars parallel to said axle and mounted on said arms, said guide means comprising arcuate guideways at each end of each support bar, members on said bars slidably received in said guideways, said thread holders comprising spindles rotatably and removably mounted on said support bars.

35 45 50 7. A thread holder comprising a base, a support mounted on said base for oscillatory motion about a horizontal axis, guide means operatively connecting said support to said base for oscillatory motion, thread holders carried by said support upon opposite sides of its axis of oscillation, said base comprising a tray having a bottom, side walls and end walls, said support being journaled in said end walls.

55 60 65 8. A thread holder comprising a base, a support mounted on said base for oscillatory motion about a horizontal axis, guide means operatively connecting said support to said base for oscillatory motion, thread holders carried by said support upon opposite sides of its axis of oscillation, said base comprising a tray having a bottom, side walls and end walls, said support being journaled in said end walls, said guide means including guideways on said end walls.

70 75 9. A thread holder comprising a base, a support mounted on said base for oscillatory motion about a horizontal axis, guide means operatively connecting said support to said base for oscil-

latory motion, thread holders carried by said support upon opposite sides of its axis of oscillation, said support including an axle journaled in bearings on said base, frame members each having angulated arms fixedly secured to said axle, support bars parallel to said axle and mounted on said arms, said guide means comprising arcuate guideways at each end of each support bar, members on said bars slidably received in said guideways, said support bars being pivoted to said arms, said members comprising pins offset from the axis on which said bars are pivoted to said arms, said pins traveling in said guideways

to rotate said bars about their pivotal connection and maintain said bars in an erect position.
